UNITED STATES PATENT OFFICE

129,537

DESIGN FOR A BROOCH OR SIMILAR ARTICLE

Eugene J. O'Brien, Burbank, Calif.

Application August 4, 1941, Serial No. 102,677

Term of patent 3½ years

o all whom it may concern:

Be it known that I, Eugene J. O'Brien, a citizen of the United States, residing at 118 North Rose Street, city of Burbank, county of Los Angeles, and State of California, have invented a new, original, and ornamental Design for a brooch or Similar Article, of which the following is a specification, reference being had to the accompanying drawing, forming part thereof.

Fig. 1 is a front elevational view of a brooch or similar article showing my new design;

Fig. 2 is a side elevational view thereof; and

Fig. 3 is a perspective view.

I claim:

The ornamental design for a brooch or similar article, as shown.

EUGENE J. O'BRIEN.
